United States Patent Office

Des. 178,718

Patented Sept. 11, 1956

178,718

AUTOMOBILE

Adam Baker Barnhart, New York, N. Y., assignor to Raymond Loewy Associates, New York, N. Y., a partnership

Application July 12, 1955, Serial No. 36,923

Term of patent 14 years

(Cl. D14—3)

Figure 1 is a side elevational view of an automobile showing my new design;

Figure 2 is a front elevational view thereof;

Figure 3 is a top plan view; and

Figure 4 is a fragmentary rear view thereof.

I claim:

The ornamental design for an automobile, as shown.
